UNITED STATES PATENT OFFICE.

ROBERT V. KAZIAN, OF NEW YORK, N. Y.

CIGARETTE-CONTAINER.

1,007,113.

Specification of Letters Patent. Patented Oct. 31, 1911

Application filed May 6, 1911. Serial No. 625,623.

To all whom it may concern:

Be it known that I, ROBERT V. KAZIAN, a citizen of the United States, and a resident of the borough of Manhattan, county, city, and State of New York, have invented certain new and useful Improvements in Cigarette-Containers, set forth in the following specification.

This invention relates to cigarette containers.

An object of the invention is to combine means with a box or case of a type already known to the art which means provides for the most ready withdrawal of the individual cigarettes from the container merely upon opening the container in the ordinary manner. To this end an inner cigarette pocket for holding the cigarettes independently of the outer case is provided. In addition, means is also provided for uptilting the inner pocket so that an individual cigarette may be withdrawn without any interference from the two parts of the outer case.

It is further an object of the invention to facilitate the packing of cigarettes in a pocket, particularly by the provision of means whereby a plurality of compartments for the pocket are provided.

The above and further objects of the invention will be apparent from the following claims which should be read in connection with the following specification as applied to the accompanying drawings, which are merely illustrative of the invention, which form a part of this application, in which like numerals designate corresponding parts, and in which—

Figure 1 is a perspective view of a complete cigarette container embodying the invention; Fig. 2 is a section through the embodiment as shown in Fig. 1; Fig. 3 is a section, drawn to an enlarged scale, through the inner pocket crosswise of the cigarettes and showing a fragmentary view of the slack links of flexible material; Fig. 4 is a development or pattern of the blank from which the inner pocket is formed; and Fig. 5 is a section corresponding to Fig. 2 but with parts broken away and showing a modification, in which the inner pocket is itself hinged to the box part of the outer case.

Referring now more in detail to the drawings, the outer case comprises the box part 1 and the lid 2 hinged to the box part by the hinge 3 and all of well known construction.

An inner pocket 4 for containing the row of cigarettes 5 is provided. This pocket 4 is formed by suitably bending and pasting together the blank 6 so that the portion 7 forms the bottom part by folding along the dotted lines indicated. The flaps 8 and 9, folded along the dotted lines indicated, are pasted together in overlapping position. Likewise the flaps 10 and 11, folded along the dotted lines indicated, are pasted together in overlapping position. In this manner the tongues 12 and 13 are caused to overlie one another. The tongue 12 is shown to be formed by the provision of two slits 14 and 15 in one side of the envelop 6 although this method of formation is merely illustrative. The pocket 4 is so formed as to completely envelop all but the exposed ends of a row of a predetermined number of cigarettes (preferably ten as indicated). That is, its total length is equal to the combined width of ten cigarettes in a row while the depth of the envelop or pocket is sufficiently less than the length of a cigarette to permit the ready withdrawal of a cigarette by manually grasping its end when presented in the position indicated in Figs. 1 and 2.

The cigarettes are packed into the pocket 4 at substantially right angles to the hinge 3 for the outer case and as shown in Figs. 1 and 2. A flexible strip 16 secured as a lining within the lid 2, as by pasting or gluing, extends from a point of detachment 90 from the lid across the hinge 3 into attachment with the pocket 4, as indicated in Figs. 1, 2 and 3. The point of attachment to the pocket and the point of detachment from the lid are respectively spaced apart from the hinge 3 thus forming a flexible and slack link joining the two parts. A similar lining for the bottom or box member 1 is attached to the other side of the pocket 4 and forms, in like manner, a slack link joining the box 1 with said pocket. The slack links 16 and 17 are so arranged and are of such lengths that the opening of the outer case causes the inner pocket 4 to be uptilted and held about midway between the box-part 1 and the lid-part 2, whether the outer case is opened bottom side up or right side up. These links may be formed of any suitable strip or sheet material.

The width of the previously described overlying tongues 12 and 13 is sufficient to overlie and span the four centrally posi-

tioned cigarettes as indicated in Fig. 3. A paper tie-band 18 which may be manufactured as a separate article by pasting together the overlapping ends 19 is slipped 5 over the tongues 12 and 13 to bind together the four central cigarettes described and also to divide the pocket 4 into three compartments *a*, *b* and *c*, as shown in Fig. 3, to hold three, four and three cigarettes, respectively. 10 This compartment-arrangement has the advantage of always preventing the falling down of the cigarettes and the holding of them in upended position when the container is opened, even when several cigarettes have 15 already been withdrawn. It is, of course, to be understood that the pocket 4 can be so bent as to slightly pinch the row of cigarettes so that the division of the pocket into compartments for holding the cigarettes upended is not essential although desirable. 20 It is also obvious that the overlying tongues 12 and 13 are not obliged to be arranged exactly as illustrated and described. This is also true of the tie-band 18. 25 Fig. 5 illustrates a modification in which the cigarette pocket 4 is hinged directly to the box 1 by a strip of paper 20 pasted to the pocket 4 and to the hinge wall 21 of the box 1, it being understood that the parts not 30 shown in Fig. 5 are constructed and formed as elsewhere illustrated and described. It is to be understood that the embodiments of the invention as set forth in this application are for purposes of illustration 35 only.

What is claimed and what is desired to be secured by United States Letters Patent is:—

1. A cigarette container comprising an outer case in two parts, one hinged to the other; an inner cigarette pocket adapted to hold the cigarettes independently of the outer case and to expose the ends of the cigarettes when packed in the pocket substantially at 40 right angles to the hinge of the outer case; and a flexible strip secured within one part of said outer case to serve as a lining therefor and extending from a point of detachment within said case as a slack link to a point of attachment with said pocket, said points of detachment and attachment being respectively spaced apart from the hinge of 45 the outer case, so that the opening of the

outer case by swinging out a part with the attached link will uptilt the cigarette pocket 55 into convenient position for the withdrawal of a cigarette.

2. A cigarette container comprising an outer case in two parts, one hinged to the other; an inner cigarette pocket adapted to hold the cigarettes independently of the outer case and to expose the ends of the cigarettes when packed in the pocket substantially at 60 right angles to the hinge of the outer case; and two flexible strips secured respectively 65 within a separate part of said outer case to serve as linings therefor and extending respectively from points of detachment within said parts as slack links to points of attachment upon opposite sides of said pocket, said 70 points of detachment and attachment being respectively spaced apart from the hinge of the outer case.

3. In combination, a cigarette box having a hinged lid; a stiff paper cigarette pocket 75 butting against the hinging wall of said box and adapted to pack cigarettes at right angles to said hinging wall; and a flexible strip secured within said hinged lid to serve as a lining therefor and extending from a 80 point of detachment within said lid as a slack link to a point of attachment with said pocket, said points of detachment and attachment being positioned to enable the opening of said hinged lid to uptilt said 85 cigarette pocket.

4. In a cigarette container an inner pocket of stiff sheet material, of a length equal to combined width of a row of cigarettes, of a depth less than the length of the cigarettes 90 and enveloping said row of cigarettes on four sides; a pair of overlying tongues projecting out at the mouth and centrally of said pocket and adapted to overlie several cigarettes at the center of said row; and a 95 tie-band embracing said tongues to bind said several cigarettes and to divide said pocket into three compartments.

In witness whereof, I have signed my name to this specification, in the presence 100 of two subscribing witnesses.

ROBERT V. KAZIAN.
